UNITED STATES PATENT OFFICE.

EDWARD H. JOHNSON, OF NEW YORK, N. Y.

TRANSPORTATION-CASE.

1,310,161.

Specification of Letters Patent. Patented July 15, 1919.

Application filed September 28, 1915. Serial No. 53,012.

To all whom it may concern:

Be it known that I, EDWARD H. JOHNSON, a citizen of the United States, and a resident of the borough of Manhattan, city of New York, county and State of New York, have invented new and useful Improvements Relating to Transportation-Cases, of which the following is a specification.

My invention relates to transportation cases for bottled liquids, such as milk, beer, etc. When bottles are carried in cases and left uncovered dust and dirt are bound to settle on and contaminate the neck rings of the bottles, thus providing a source for contaminating the liquid which later has to be poured out.

My invention has for its object to construct a case that will protect the bottles from dust and dirt and that will also enable the proper cooling of the bottles with the use of ice without direct contact between the ice and the bottles and without any chance of the water from the melted ice reaching the caps and necks of the bottles.

This protection against the ice and water is of importance when the bottles are of paper or similar material and there is also removed a possible source of contamination such as may be caused by placing ice in direct contact with the bottles.

For the accomplishment of the above mentioned objects I divide my transportation case in two sections, a lower section and an upper section. The former is in the form of a box or deep pan and is provided with means for spacing the bottles with guides for insuring the proper position of the top section relative to the bottom section and with handles which serve to support the case whereby it can be carried. The upper section is in the form of a shallow pan. It has a bottom with openings of a suitable size and form for the bottles. These openings are covered with caps and are located so as to correspond to the spacing provided for in the lower section. Each of the caps is conical or pyramidal or otherwise conforms more or less to the shape of the upper part of the bottle. The spaces between these caps themselves as well as be-

tween the outer ones and the sidewalls of the upper section can be filled with ice and no ice or water whatsoever can reach the interior of the lower compartment containing the bottles, which compartment becomes practically

airtight and dustproof when the upper section of the case is placed in position in the lower section. 55

For a clearer understanding of my invention reference is made to the accompanying drawing forming a part of this specification, 60 in which drawing

Figure 1 represents a longitudinal and vertical section through an assembled case, and

Fig. 2 is a top view of the case. In the last mentioned figure a portion of the upper 65 section has been removed.

In the drawing 1 denotes the upper section and 2 the lower section of the case and it will be observed that the lower section is in the form of a box or deep pan while the upper 70 section is in the form of a shallow pan or liquid-tight receptacle which is open at the top. The bottom plate 3 of the upper section has upstanding edge portions and a flat portion with openings 4 for the bottles to pass 75 through and these openings are covered by caps 5. The caps 5 may be considered as constituting inverted cup-shaped portions on the under side of the liquid-tight receptacle for receiving the upper ends of the bottles where- 80 by the lower portions of the liquid-tight receptacle or means may be considered to extend below the tops of the bottles when the latter are in place in the transportation case.

The lower section 2 has circular seats 6 which the bottles fit and which thus serve the purpose of spacing the bottles. Guides for insuring the proper relative position between the upper and the lower section are indicated by the numeral 7. They are shown as consisting of angle irons secured vertically at the corners. These angle irons are shown connected at the top by bands 8 to increase the rigidity. Supporting handles 9 are secured at each end of the lower section. The 95 upper section 1 is provided with handles 10 hinged on the inside.

It is evident that my invention lends itself to a great variety of constructional modifications, and I do not wish to limit myself, 100 therefore, to any particular details shown in the drawing and described in connection therewith.

In my transportation case the bottles can be removed without disturbing the ice and 105 this factor is bound to have a considerable influence on the ice consumption; also the possibility of mixing the ice with salt or of

using some other cooling mixture without any risk of the necks of the bottles becoming tainted by salt or other chemicals adds greatly to the economy of icing.

5. What I claim is:

1. In a transportation case for bottled liquids an upper section, a lower section having means for spacing the bottles, means on the lower section for supporting the 10 weight of the case for carrying purposes, and means for insuring the proper position of the upper section relative to the lower section, when assembled, said case being constructed so that said upper and lower sections coöperate to provide an inclosure or compartment for the bottles, the upper section forming a liquid-tight means for holding a cooling medium and which liquid-tight means has inverted cup-shaped portions 15 on its under side to provide receiving spaces for the top of the bottles whereby the bottom of said liquid-tight means extends below the tops of the bottles.

2. A transportation case comprising in 25 combination a lower section or box having therein means for holding bottles in spaced relation, and an upper section which fits into the lower section, said upper section being in the form of a pan and having in its bottom portion openings which correspond to the spacings provided for in the lower section, said upper section also having a cap which covers each of said openings and the upper section being shaped so that the 30 spaces between the caps themselves and between the outer caps and the sidewalls of the upper section can be filled with ice.

3. A transportation case of the class described comprising in combination an upper 40 and a lower section which provide between them a practically air-tight chamber; the lower section having at each corner thereof vertically extending angle-irons that serve as guideways said angle-irons being connected at their top by bands which increase 45

rigidity of the structure, said lower section also being provided with handles whereby the case can be transported, the upper section being in the form of a pan having openings in the bottom to receive the upper portions of bottles, each of which openings are covered with a cap, the caps being spaced from each other and also from the walls in the upper section; said upper section also having handles whereby the section can be lifted from the lower section. 50

4. A transportation case of the class described comprising in combination a lower section, and an upper section constructed so as to hold water and so as to fit the lower 55 section, the sections being constructed so as to provide between them a practically air-tight and dust-proof space, the upper section comprising a bottom plate and caps, the bottom plate having upstanding edge 60 portions and a flat portion with openings therein, the caps being located so as to cover said openings and being connected to said bottom plate so as to provide a liquid tight pan or receptacle. 65

5. A transportation case for bottles which transportation case comprises a bottom section upon which the bottles are supported and an upper section that covers the bottles, the bottom section having means for holding the bottles in spaced relationship, the upper section having a bottom member with upstanding edges and caps corresponding in number to the bottles which the bottom section is constructed to hold, the caps being 70 connected to the bottom member so that the bottom member and caps provide a liquid-tight pan or receptacle within which a cooling substance can be placed. 75

This specification signed and witnessed 80 this 21st day of September, A. D., 1915.

EDWARD H. JOHNSON.
